(57) **CLAIM**

The ornamental design for a cable guide, as shown and described.

DESCRIPTION

FIG. 1 is a perspective view showing an embodiment of the new design for a cable guide, including a mounting tape, such as, e.g., a high-strength, double-sided acrylic foam tape, for mounting the cable guide; FIG. 2 is a top view thereof;

FIG. 3 is a bottom view thereof;

FIG. 4 is a left side view thereof;

FIG. 5 is a right side view thereof;

FIG. 6 is a rear view thereof;

FIG. 7 is a front view thereof; and,

FIG. 8 is a perspective view of the cable guide of FIG. 1 in use, mounted to a headgear.

The broken line showing forms no part of the claimed design, and the shading is provided to illustrate contour only and is not an indication of texture, gloss, etc.
